PULL TOY

Irving Gould, Philadelphia, Pa., assignor to Wilkening Manufacturing Company, Philadelphia, Pa., a corporation of Delaware

Application January 10, 1957, Serial No. 44,468

Term of patent 7 years

(Cl. D34—2)

Fig. 1.

Fig. 2.

Fig. 3.

Fig. 4.

Figure 1 is a perspective view of a pull toy showing my new design; the pull toy being shown in relatively retracted position as compared to Fig. 2;

I claim:

The ornamental design for a pull toy, as shown and described.
